UNITED STATES PATENT OFFICE.

JEAN CHABANEL, OF PARIS, FRANCE.

APPARATUS FOR SEPARATING, FILTERING, AND DISINFECTING FECAL MATTERS.

SPECIFICATION forming part of Letters Patent No. 406,161, dated July 2, 1889.

Application filed January 11, 1889. Serial No. 296,051. (No model.)

To all whom it may concern:

Be it known that I, JEAN CHABANEL, of the city of Paris, France, have invented Improved Apparatus for Separating, Filtering, and Dis- 5 infecting Fecal Matters, of which the following is a full, clear, and exact description.

My invention relates to apparatus for separating, filtering, and disinfecting fecal matters, and has for its object to insure efficient 10 working, and enables the apparatus to be emptied without stoppage to its working.

Reference is to be had to the accompanying drawings, forming part of this specification, which represent an example of the improved 15 apparatus, Figure 1 being an elevation, Fig. 2 a top plan, and Fig. 3 a vertical central section thereof. Figs. 4, 5, and 6 show details hereinafter referred to.

The same letters of reference serve for like 20 parts in all the figures. *a* is the soil-pipe communicating at its lower end with the upper part *b* of the separator, the orifice being closed by a sliding screen *c*, working in connection with the piston *d*, as hereinafter de- 25 scribed. Beneath the separator *b* is a receptacle *e*, supported upon a table *f*, mounted upon a screw *g*, operated by a hand-wheel *h*, for the purpose of maintaining a tight closure between the bottom of separator *b* and the 30 mouth of receptacle *e*, with the aid of a packing-ring *i*. The screw is prevented from loosening under the weight by a ratchet and pawl *h'*.

Fig. 3 shows the apparatus as closed for the 35 purpose of enabling the filled receptacle to be removed and replaced by an empty one, the mouth of the soil-pipes *a* being closed by the screen *c*, so as to prevent the admission of solid matters above the piston *d*. This 40 latter is mounted upon the lower end of a screw *m*, provided with a cross-handle *j*, and is pressed against the internally-flanged mouth of separator *b*, a perfectly-tight joint being insured by means of an elastic ring *k*, 45 Fig. 4, inserted in an annular groove made in the under face of piston *d*. The receptacle *e* may then be removed without leakage from the separator *b*. A cock is provided on the receptacle *e*, by which to draw off a portion 50 of the contents in case it should be too full.

When an empty receptacle has been placed in position and a tight joint made with the

mouth of separator *b*, the piston *d* is raised by turning screw *m*, the piston being prevented from turning by an arm *n* attached 55 thereto, whose free end slides in a vertical guide *o*, and on meeting a lug at the upper part of the screen *c*, carries the latter up with it, the screen having been closed, as above mentioned, by the said arm *o* striking a similar lug at the lower part of the screen on the descent of the piston. The piston *d* is also provided with a ring *p*, of leather or other suitable material, projecting slightly beyond its periphery for scraping the sides of the 60 perforated cage *q*, and keeping it constantly clean. The piston *d* need not fit the cage *q* very tightly, but if does, it would be notched at the edge to receive the guide *o*, as indicated in Fig. 6. 70

The liquid escapes at an overflow-pipe *r*, Fig. 1, to the end of which may be attached a double strainer *s*, Fig. 5, whereby the liquid is filtered after being disinfected by a disinfectant constantly supplied at the orifice *t* in 75 the cover.

In order to avoid or remedy any clogging of the soil-pipe *a*, the overflow-pipe *r* is connected with the vessel *b* at a lower level through a pipe and cock *u*, by which the 80 liquid can be drawn off below the orifice of the soil-pipe, and thus enable the latter to be freed from the obstruction, after which cock *u* would be closed and the liquid again allowed to flow out from the higher level, as 85 before.

v v are man-holes in the cover to give access to or enable the interior of the apparatus to be inspected.

By means of the cage or perforated vessel 90 placed in the upper part of the apparatus, combined with the rising and falling screen or shutter, and piston operated by the screw *m*, not only can the upper part be hermetically closed while the lower receptacle is being removed, but the solid matters also can be forced into the receptacle in a suitably-compact condition. This is assisted by the cock *l*, which allows of running off a portion of the liquid before removal, so as to prevent 95 any overflow.

The apparatus operates substantially as follows: When the vessels *b* and *e* are united and the piston *d* raised, together with the

screen *c*, so that the lower end of the pipe *a* shall be open, the matter is introduced through the pipe *a* and enters the perforated cage *q*, and drops thence into the receptacle 5 *e* in a substantially loose condition; and when that receptacle *e* is full, the matter continuing to flow through the pipe *a* will enter and remain in the cage *q* until the cage is full to the lower face of the piston *d*. Pressure is 10 now applied to the piston *d* and the same forced downward, so as to compact the solid matter into the lower vessel *e*, while liquid matter will be allowed to escape through the pipe *r* from the vessel *p*. When the piston 15 *d* has reached its lowermost position the vessel *e* is full of the compacted solid matter, and may be removed and another put in its place. This entire operation depends of course upon the production of a properly tight joint 20 between the vessels *b* and *e*.

I claim—

1. The combination of the vessel *b*, with the inner perforated cage *q*, with the inlet-pipe *a*, leading into said cage, and with the piston 25 *d* within said cage, said piston being provided with the lower packing-ring *k* and the circumferential scraper *p*, substantially as and for the purpose herein shown and described.

2. The combination of the vessel *b* and inner perforated cage *q*, and inlet-pipe *a*, leading to said cage, with the piston *d*, adapted to move within said cage, and with the slide *c*, which is adapted to be moved up and down by said piston to open and close the inlet-pipe, as specified. 30

3. The combination of the vessel *b*, inner perforated cage *q*, inlet-pipe *a*, slide *c*, and piston *d*, with the lower vessel *e*, table *f*, and screw *g*, substantially as and for the purpose specified. 40

4. The combination of the vessel *b*, inner perforated cage *q*, inlet-pipe *a*, leading to said cage, slide *c*, piston *d*, and overflow-pipe *r*, having branch *u*, with the lower receiving vessel *e*, and vertically-movable table *f*, for 45 supporting said vessel *e*, as specified.

The foregoing specification of my improved apparatus for separating, filtering, and disinfecting fecal matters signed by me this 3d day of December, 1888.

JEAN CHABANEL.
